United States Patent Office.

AUGUSTUS DAY, OF DETROIT, MICHIGAN.

Letters Patent No. 89,385, dated April 27, 1869.

WASH-BOILER.

The Schedule referred to in these Letters Patent and making part of the same.

To whom it may concern:

Be it known that I, AUGUSTUS DAY, of Detroit, in the county of Wayne, and State of Michigan, have invented a new and useful Improvement in Clothes-Washing Boilers; and I do declare that the following is a true and accurate description thereof, reference being had to the accompanying drawings, and to the letters of reference marked thereon, and being a part of this specification.

Figure 1 is a perspective view of my boiler with cover removed.

Figure 2 is a longitudinal sectional representation of the cover.

Figure 3 is a representation of the interior apparatus.

Figure 4 is a view of one of the loose ends.

Like letters indicate like parts in each figure.

The nature of this invention relates to an improvement in that class of boilers in which the cleansing of the garments is performed by the currents of hot suds circulating in steady currents from the bottom upward through proper channels, and then downward through the clothes.

The invention consists in a loose convex, perforated or slatted false bottom, and in loose plates, extending from the bottom of the boiler nearly to the top.

These plates are designed to stand vertically in the ends of the boiler in such a manner as to convert these ends into channels, through which the water circulates.

It also consists in placing fillets in the ends of the cover, so that they will, when the cover is in position, be immediately over the top of said channels, and which act to turn the water over the clothes.

A, in the drawings, represents a boiler of the ordinary construction, into the bottom of which is placed the loosely-fitting perforated or slatted convex bottom B.

C are plates, of tin or other appropriate metal, with a circular notch in the bottom to allow of the water passing freely.

These plates should be a little wider at bottom than at top, and should be placed vertically in each end of the boiler, at the ends of the false bottom, and are designed to cut off the ends of the boiler from the centre and convert them into channels through which the water is conveyed from the bottom to the top of the boiler, where it strikes the fillets D, which are secured to the under side of the cover E; and by these fillets a direction is given to the currents of water toward the centre of the boiler, where it spreads over the clothes, and, percolating through them, carries the dirt with it to the bottom of the boiler, whence the water is again conducted to the top, and the operation continued as long as may be necessary to complete the cleansing process.

The clothes occupy the chamber above the false bottom, and between the plates C.

To operate the apparatus, water should be placed in the bottom, sufficient to cover the false bottom, and the clothes then placed in the boiler with a sufficient amount of soap or other detergent. When the water commences to boil, the same will rise through the channels and flow over the clothes in the manner described.

What I claim as my invention, and desire to secure by Letters Patent, is—

The wash-boiler described, consisting of the boiler A, convex perforated false bottom B, end plates C, and cover F, with fillets D, the whole being combined as described, for the purpose set forth.

AUGUSTUS DAY.
